UNITED STATES PATENT OFFICE

2,473,243

COATING MACHINE FOR FLEXIBLE SHEET MATERIALS

Joseph Ettl, Brooklyn, N. Y., assignor to Rogers Industries, Inc., New York, N. Y., a corporation

Application July 3, 1946, Serial No. 681,376

6 Claims. (Cl. 91—50)

1
This invention relates to a gluing or strip coating machine and an object of this invention is to provide a machine which will efficiently apply an adhesive to vellum, cardboard, sheets of paper, etc.

In practice with prior machines it has been found that due to the necessity of making two individual adjustments, that is, one adjustment of the feed rollers from the coating roller and then a second adjustment of the supply roller from the coating roller, that the application of the glue to the material to be coated was purely guess work, generally too much glue on the coating roller would reach the feed rollers and cause an excess deposit of glue on the opposite side of the material being coated. This excess glue spoiled the material and necessitated the entire stoppage of the machine to clean the feed rollers.

In the mechanism herewith disclosed, only a single adjustment is required. This single adjustment provides a safety feature, the prevention of depositing excess adhesive onto the feed rollers. The coating roller is made to move from both the supply roller and the feed rollers simultaneously when an increased or decreased amount of adhesive is required on the coating roller.

Furthermore, in practice it has been proven that the amount of adhesive deposited on the coating roller depends upon the distance between the supply roller and the coating roller, and that when the amount of adhesive on the coating roller is increased, that the surface of the coating deposited upon the coating roller increases in roughness of the surface of the adhesive.

In other words, heavy ridges are formed in the coating surface, depending upon the consistency of the adhesive, the said ridges being higher than the normal adjustment of the coating would ordinarily indicate.

In order to compensate for this unevenness of the coating surface, I have positioned the axis of the supply roller at a sixty degree angle below the horizontal line passing through the axis of the coating roller and I have positioned the median line between the feed rollers at a thirty degree angle above the said horizontal line.

This arrangement of the roller positions causes a greater opening to be formed between the feed rollers and the coating roller than the opening between the coating roller and the supply roller for an equal amount of horizontal movement of the coating roller to or from the set position of the supply roller.

With the above and other objects in view, the invention will be hereinafter more particularly described, and the combination and arrangement

of parts will be shown in the accompanying drawings and pointed out in the claims which form part of this specification.

Reference will now be had to the drawings, wherein like numerals of reference designate corresponding parts throughout the several views, in which:

Figure 1 is a side elevation of my improved coating machine.

Figure 2 is a cross-sectional view, the section being taken as on line 2—2 in Figure 1.

Figure 3 is an enlarged assembly view of a fragmentary portion of the machine showing a preferred arrangement of the relative positions 15 of the coating roller, supply roller, feed rollers and coating adjustment means.

In the illustrated embodiment of the invention, the numeral 10 indicates a gluing or coating machine comprising a receptacle 11 having upright 20 side walls 12.

Rotatably mounted in the walls 12 in sealed bearings 13 is an adhesive pick-up roller or supply roller 14. The sealed construction of the bearings 13 makes it possible to mount the bearings 25 below the level of the adhesive and fully immersed in the adhesive, and to mount the supply roller 14 with about four-fifths of its diameter immersed in the adhesive.

The side walls 12 also provide bearings for a 30 coating roller 15 carried by a shaft 16. The shaft 16 is rotatably mounted in rectangular guide blocks 17 which are slidably mounted in guideways 18. The guideways extend through the side walls 12 so as to form openings for the shaft 16.

Each side wall 12 also provides a rectangular guideway 20 which is in angular relation with each of the guideways 18. A bar 21 is secured to the wall 12 by screws 22 and covers each guideway 20.

40 A carrier 23 is slidably mounted in each guideway 20 and provides bearings for material feed rollers 25. Fixed in the carrier 23 by a pin 26 is a threaded member 27 which passes outwardly through an aperture in the bar 21. A coil spring 45 28 is mounted on the threaded member 27 intermediate the carrier 23 and the bar 21 and urges the feed rollers in direction of the coating roller 15.

A threaded nut 29 on the member 27 serves for 50 moving the feed rollers in a direction away from the coating roller. After adjusting the feed rollers 25 they remain set during operation of the coating machine 10.

Each side wall 12 has a tubular aperture 30 in 55 which a pin 31 is slidably mounted. One end of

the pin 31 is seated in an aperture 32 in one of the guide blocks 17. A pin 33 is mounted in the aperture 30 and is fixedly held therein by a screw 34.

A compressed coil spring 35 is placed in the aperture 30 intermediate the pins 31 and 33 and urges the slide block 17 and the coating roller 15 in the direction of the supply roller 14 and the feed rollers 25.

Rotatably mounted in the side walls 12 is an adjustment rod 37 having a threaded end portion 38. An adjusting dial 39 is secured to the rod 37 by a pin 40. The dial 39 is calibrated as shown at 41. A pointer 42 is secured to a side wall 12 of the receptacle 11 and extends in overlapping relation with the dial 39 and indicates the set position of the dial. A nut 43 threaded on the end portion 38 serves to lock the dial 39 in set position. It is to be noted that the hub of the dial has a slot 44 through which the pin 40 passes outwardly. The slot 44 extends through the hub and provides clearance space for movement of the pin therein.

As best shown in Fig. 3, the adjustment rod 37 has cam means 45 formed near each end of the rod by eccentrically turning out portions thereof in alignment with the walls 12. Cam blocks 46 are slidably mounted in an extension 30' of the aperture 30. The cam blocks 46 are in alignment with the cam means 45. Adjusting screws 47 are threaded in the cam blocks 46 at one end and in engagement with the slideable blocks 17 at the opposite end.

Each screw 47 has apertures 48 in which an elongated pin may be inserted for adjusting the screw with relation to a cam block 46. It will thus be seen that the springs 35 urge the bearing blocks 17 and the coating roller 15 in direction of the supply roller 14 and the feed rollers 25, whereby a single adjustment of the coating roller 15 causes movement of the coating roller 15 to or from both the supply roller 14 and the feed rollers 25 simultaneously.

I provide a heating chamber 50 for oil below the supply roller 14 for heating the supply roller. For the purpose of effectively circulating the oil in the heating chamber 50, I provide a shaft 51 having right-hand and left-hand rotors 52. The rotor arrangement shown serves to move the oil from the middle of the heating chamber towards the ends thereof. In the chamber 50 is a heater 54.

Secured to the coating roller shaft 16 is a pinion gear 55 which meshes with a gear 56 driven by a motor (not shown). The gear 56 is secured to the supply roller shaft 57. Secured to the shaft 16 is a gear 58 which meshes with pinion gears 59 secured to reduced end portions of the feed rollers 25. Rotation of the gear 56 causes rotation of all the gears and the rollers actuated thereby.

It is to be noted that the axes of the supply roller 14 and the feeding rollers 25 are positioned on the same side of a vertical plane passing through the axis of the coating roller 15.

In accordance with the patent statutes, I have described and illustrated the preferred embodiment of my invention, but it will be understood that various changes and modifications can be made therein without departing from the spirit of the invention as defined by the appended claims.

I claim:

1. In a gluing or coating machine, the combination with a receptacle for adhesive, a supply roller rotatably mounted in said receptacle with the supporting bearings thereof sealed while immersed

in said adhesive, a coating roller rotatably mounted in bearings above the level of adhesive in said receptacle, said coating roller being parallel to the axis of said supply roller, the lower face of said coating roller being above the upper surface of said adhesive, said coating roller being slidably mounted for movement to and from said supply roller while being out of contact with said adhesive, lockable dial adjustment means for movement of said coating roller, material feed rollers positioned above the horizontal center line of said coating roller and being movable relative to said coating roller, said feed rollers being in set position during operation of said machine, whereby a single adjustment of said coating roller causes movement of said coating roller to or from both said supply roller and said feed rollers simultaneously, the axes of said supply roller and said feeding rollers being positioned on the same side of a vertical plane passing through the axis of said coating roller.

2. In a gluing or coating machine, the combination with a receptacle for adhesive, a supply roller rotatably mounted in said receptacle with the bearings thereof sealed while immersed in said adhesive, a coating roller rotatably mounted above the level of said adhesive, the lower face of said coating roller being above the upper surface of said adhesive, said coating roller being slidably mounted for movement to and from said supply roller while parallel to the axis of said supply roller and out of contact with said adhesive, material feed rollers movable to set position relative to said coating roller, the axis of said coating roller being positioned horizontally, the plane in which the axis of said supply roller is positioned passes through the axis of said coating roller and makes an angle with and below a horizontal plane passing through the axis of said coating roller, the median line between said feed rollers being positioned at a smaller angle above said horizontal plane, a coating adjustment rod having cam means for said parallel movement of said coating roller, whereby a single adjustment of said coating roller causes movement of said coating roller from both said supply roller and said feed rollers simultaneously, the opening between said coating roller and said feed rollers being greater than the opening between said coating roller and said feed rollers, the axes of said supply roller and said feeding rollers being positioned on the same side of a vertical plane passing through the axis of said coating roller.

3. In a gluing or coating machine, the combination with a receptacle for adhesive, a supply roller rotatably mounted in said receptacle with the supporting bearings thereof sealed while immersed in said adhesive, a coating roller rotatably mounted in bearings above the level of adhesive in said receptacle, said coating roller being parallel to the axis of said supply roller, the lower face of said coating roller being above the upper surface of said adhesive, said coating roller being slidably mounted for movement to and from said supply roller while being out of contact with said adhesive, lockable dial adjustment means for movement of said coating roller, material feed rollers positioned above the horizontal center line of said coating roller and being movable relative to said coating roller, said feed rollers being in set position during operation of said machine, said machine having side walls, guideways in said side walls, bearing blocks for said coating roller slideable in said guideways, spring means urging said bearing blocks and said coating roller in direction

of said supply roller and said feed rollers, a co-acting adjustment rod having cam means for said parallel movement of said coating roller, cam blocks, adjusting screws threaded in said cam blocks at one end and being in engagement with said slidable blocks at the opposite end, whereby a single adjustment of said coating roller causes movement of said coating roller to or from both said supply roller and said feed rollers simultaneously, the axes of said supply roller and said feeding rollers being positioned on the same side of a vertical plane passing through the axis of said coating roller.

4. In a gluing or coating machine, the combination with a receptacle for adhesive, a supply roller rotatably mounted in said receptacle with the bearings thereof sealed while immersed in said adhesive, a coating roller rotatably mounted above the level of said adhesive, said coating roller being parallel to said supply roller, the lower face of said coating roller being above the upper surface of said adhesive, said coating roller being slidably mounted for movement to and from said supply roller while parallel to the axis of said supply roller and out of contact with said adhesive, lockable adjustment means for movement of said coating roller, material feed rollers movable relative to said coating roller, the axis of said coating roller being positioned in a horizontal plane, the axis of said supply roller being positioned in a plane lying at a sixty degree angle below said horizontal plane and passing through the axis of said coating roller, the median line between said feed rollers being positioned in a plane lying at a thirty degree angle with said plane and passing through the axis of said coating roller, whereby a single adjustment of said coating roller causes movement of said coating roller from both said supply roller and said feed rollers simultaneously, the opening between said coating roller and said feed rollers being greater than the opening between said coating roller and said feed rollers, the axes of said supply roller and said feeding rollers being positioned on the same side of a vertical plane passing through the axis of said coating roller.

5. In a gluing or coating machine, the combination with a receptacle for adhesive, a supply roller rotatably mounted in said receptacle with the bearings thereof sealed while immersed in said adhesive, a coating roller rotatably mounted above the level of said adhesive, the lower face of said coating roller being above the upper surface of said adhesive, said coating roller being slidably mounted for movement to and from said supply roller while parallel to the axis of said supply roller and out of contact with said adhesive, lockable adjustment means for movement of said coating roller, material feed rollers, settable relative to said coating roller, the axis of said coating roller being positioned in a horizontal plane, the axis of said supply roller being positioned in a plane lying at an angle below said horizontal plane

and passing through the axis of said coating roller, the median line between said feed rollers being positioned in a plane lying at a smaller angle with said plane and passing through the axis of said coating roller, whereby a single adjustment of said coating roller causes movement of said coating roller from both said supply roller and said feed rollers simultaneously, the opening between said coating roller and said feed rollers being greater than the opening between said coating roller and said feed rollers, the axes of said supply roller and said feeding rollers being positioned on the same side of a vertical plane passing through the axis of said coating roller.

6. In a gluing or coating machine, the combination with a receptacle for adhesive, a supply roller rotatably mounted in said receptacle with the bearings thereof sealed while immersed in said adhesive, a coating roller rotatably mounted above the level of said adhesive, the lower face of said coating roller being above the upper surface of said adhesive, said coating roller being slidably mounted for movement to and from said supply roller while parallel to the axis of said supply roller and out of contact with said adhesive, lockable adjustment means for movement of said coating roller, material feed rollers, settable relative to said coating roller, the axis of said coating roller being positioned in a horizontal plane, the axis of said supply roller being positioned in a plane lying at an angle below said horizontal plane and passing through the axis of said coating roller, the median line between said feed rollers being positioned in a plane lying at a smaller angle with said plane and passing through the axis of said coating roller, whereby a single adjustment of said coating roller causes movement of said coating roller from both said supply roller and said feed rollers simultaneously, the opening between said coating roller and said feed rollers being greater than the opening between said coating roller and said feed rollers, an oil heating chamber below said adhesive supply roller for heating said roller, and means for circulating heating oil in said heating chamber, said means comprising rotatable spaced-apart impellers causing motion of said oil from the mid-portion of said chamber towards the end thereof, the axes of said supply roller and said feeding rollers being positioned on the same side of a vertical plane passing through the axis of said coating roller.
